UNITED STATES PATENT OFFICE.

EDWARD BACH, OF LIVINGSTON, MONTANA.

AUTOMATIC GATE.

1,343,023.

Specification of Letters Patent. Patented June 8, 1920.

Application filed March 18, 1920. Serial No. 366,899.

To all whom it may concern:

Be it known that I, EDWARD BACH, a citizen of the United States, residing at Livingston, in the county of Park, State of Montana, have invented certain new and useful Improvements in Automatic Gates; and I do hereby declare the following to be a full, clear, and exact description of the invention, such as will enable others skilled 5 in the art to which it appertains to make and use the same.

This invention relates to new and useful improvements in gates and particularly to automatically opening and closing gates.

15 One object of the invention is to provide a novel and improved means for mounting a pair of sliding gates whereby they may be easily and quickly moved into open position, and which will readily gravitate into closed 20 position.

Another object is to improve the means actuated by an approaching vehicle for moving the gates into open position.

Other objects and advantages will be apparent from the following description when taken in connection with the accompanying drawing.

In the drawing:

Figure 1 is an elevation of a pair of gates 30 made and mounted in accordance with the present invention and shown in closed position.

Fig. 2 is an elevation of the same showing the gates in open position.

35 Fig. 3 is a top plan view of the same, with the gates in closed position.

Fig. 4 is a vertical sectional view through one of the inner posts, on the line 4—4 of Fig. 2.

40 Referring particularly to the accompanying drawing, 10 represents the pair of inner posts, and 11 the pair of outer posts, said latter posts being arranged in alinement with each other and with the posts 10. Each 45 of the posts is vertically and longitudinally bifurcated, as shown at 12, and slidable through the bifurcations are the gates 13.

As the construction of one gate and the associated parts of the opening mechanism 50 are identical with those of the other gate, a description of one is deemed sufficient.

Through each of the posts 10 and 11 there is disposed a bolt 14 which rides in an inclined slot 15 formed in the gate. Thus, 55 as the gate slides toward open position, the links, so as to raise the bar 16 into its normal

gate will move vertically in the bifurcations of the posts 10 and 11.

Extending across the gateway, between the inner posts 10, is a horizontal bar 16, on each end of which is secured a pair of 60 rigid links or arms 17, the said arms extending longitudinally away from the said ends of the bar. Pivottally mounted on each side of the post 10 is an angle lever, represented as a whole by the character A, the shorter 65 arm 18 of which is pivotally connected with an arm 17, by means of a vertical link 19. Pivottally connected to the gate, between the posts 10 and 11, is a normally horizontal link 20, the other end of which is pivotally 70 connected with the outer end of the longer arm 21 of the angle lever. As seen in the plan view, Fig. 3, there are two of the arms 17, as well as two of the links 19, the angle levers A, and the links 20, the pairs of such 75 parts being properly mounted on opposite sides of the gate. It will also be noted that each gate has two of the inclined slots 15, for passage therethrough of the bolts 14 carried by the gate posts 10 and 11. 80

Disposed at opposite sides of the gateway are the inclined channel members 22, the inner or higher ends of which are movably connected with the bar 16. These channel members are disposed in parallel spaced relation for the reception of the wheels of an approaching vehicle, whereby when the weight of the vehicle engages on said channel members the bar 16 will be depressed with the result that the links 19 will rock 85 90 the angle levers A and slide the gates into open position. As the gates move through the bifurcations of the posts 10 and 11, they will ride upwardly on the transverse bolts 14, which are disposed through said posts. 95 Then, when the vehicle passes through the gateway, and down the other pair of channel members, at the other side of the gateway, the gates will gravitate into closed position.

It will be noted that the horizontal links 100 20 are offset at 20' so as to permit easy passage past the posts 10. The bolts 18', on which the angle levers are mounted, extend through the posts 10, and on these bolts, within the bifurcations of the posts, 105 the gates are supported.

The combined weights of the gates are sufficient to permit them to gravitate into closed position and actuate the angle levers and 110 the links, so as to raise the bar 16 into its normal

position, and the inclined channel members into position for operation from either side of the gateway.

What is claimed is:

- 5 In an approach opening gate, the combination with a plurality of aligned and bifurcated posts, transverse bolts disposed through the posts, a pair of gates slideable within the bifurcations of the posts and
- 10 having longitudinal and inclined slots receiving the said bolts therethrough, a bar disposed horizontally between the inner of the posts and extending across the gateway,

inclined approaches movably connected with the bar and extending away from the opposite sides of the gateway, angle levers pivotally mounted on the said inner posts, links connected to the angle levers and to the gates, and links connected to the angle levers and to the ends of the said bar.

In testimony whereof, I affix my signature, in the presence of two witnesses.

EDWARD BACH.
